UNITED STATES PATENT OFFICE.

PHILIP J. KENT, OF DETROIT, MICHIGAN, ASSIGNOR TO CHRYSLER CORPORATION, OF DETROIT, MICHIGAN, A CORPORATION OF DELAWARE.

DESIGN FOR AN AUTOMOBILE PARKING LAMP.

Application filed October 9, 1925. Serial No. 15,073. Term of patent 14 years.

To all whom it may concern:

Be it known that I, PHILIP J. KENT, a citizen of the United States of America, residing at Detroit, in the county of Wayne and State of Michigan, have invented a new, original, and ornamental Design for Automobile Parking Lamps, of which the following is a specification, reference being had to the accompanying drawings, forming a part thereof, in which—

Fig. 1 is a top plan view of a parking lamp showing my new design.

Fig. 2 is a side elevation of a parking lamp.

Fig. 3 is an end view of a parking lamp.
What I claim is:

The ornamental design for an automobile parking lamp as shown.

PHILIP J. KENT.
